BAFFLE TYPE MUFFLER

William Keller, Flint, Mich.

Application December 11, 1950, Serial No. 200,216

2 Claims. (Cl. 181—67)

1

The present invention relates to mufflers and more particularly to mufflers of the type commonly used in the exhaust systems of internal combustion engines.

The principal object of the invention is to provide a novel and improved muffler which will render the maximum silencing effect with the minimum amount of back pressure.

Another object of the invention is to provide a muffler which can be manufactured in mass production with the fewest number of differently shaped parts and one that can be assembled without the use of complicated fixtures and jigs for properly spacing and supporting the elements at their locations relative to one another during the attachment thereof together.

A further object of the invention is to provide a muffler as set forth in the preceding objects wherein identical baffles of a unique construction are associated in reverse positions relative to the baffles adjacent thereto for producing alternate size and shaped chambers and which will cause a helical motion of the exhaust gases in a single direction while passing through openings in the baffles, said openings in each baffle being of a size equivalent to the area of the entrance opening to the muffler.

It is also an object of the invention to provide a muffler of the above-indicated character which is simple and substantial in construction, economical to manufacture, and thoroughly efficient and practical in use.

These, together with various auxiliary features and objects of the invention which will later become apparent as the following description proceeds, are attained by the present invention, a preferred embodiment of which has been illustrated, by way of example only, in the accompanying drawings, wherein:

Figure 1 is a central longitudinal section through the improved muffler, showing some of the baffles in elevation and others in section;

Figure 2 is a cross section taken on line 2—2 of Figure 1; and

Figure 3 is a diagrammatic view, illustrating in full and dotted lines the helical motion of exhaust gases while passing through the muffler.

Referring now more specifically to the accompanying drawings, wherein like numerals designate similar parts throughout the various views, the numeral 10 indicates a tubular casing which has attached to the opposite ends thereof, by welding or any other approved method, closure members 11 and 12 with flanged inlet and out-

2

let openings 13 and 14, respectively. The flange of the inlet opening 13 is adapted to be connected to the exhaust pipe leading from an engine, while the flange of the outlet opening 14 is for connection to the pipe from which the exhaust gases are discharged to the atmosphere. Both enclosure members 11 and 12 are preferably formed to the same size and shape for minimizing the number of parts of different construction.

Within the tubular casing 10 is arranged a number of identically constructed circular cross walls in the form of baffles 15, there being six shown for the purpose of illustration. Each baffle consists of a substantially cone-shaped wall 16 having a plurality of spaced louvers 17 formed therein and a cylindrical flange 18 formed at the periphery or base of said wall of a size whereby the outer surface of said flange snugly engages the inner surface of the tubular casing 10. The louvers 17 in each baffle are likewise identical and are preferably of a number and opening size equal to the area of the opening 13 through which exhaust gases enter the muffler for reducing back pressure. Also, all louvers 17 of each baffle extend radially from a location near the apex 19 of the bellied cone-shaped wall 16 to a location adjacent the cylindrical flange 18, and all are formed so that the angle of the walls of the louvers at their openings directs gases passing therethrough in a helical direction.

As shown in Figure 1, the identical baffles 15 are so constructed that reversing the positions of adjacent baffles in the casing by first contacting their apexes 19 and then the edges of their cylindrical flanges 18 provides alternate size and shaped expansion chambers 20 and 21 between the different baffles, and gases passing through all baffles are directed in the same helical direction. All of the flanges 18 of the baffles 15 or, if desired, only the flanges of the end baffles are attached to the casing 10 by spot welding for holding the baffles in proper position in the casing and for providing end gas expansion chambers 22 and 23 forwardly and rearwardly of the baffles. Abutting apexes of adjacent baffles may also be welded together if so desired.

The diagrammatic illustration, Figure 3, shows with full- and dotted-line arrows 24 and 25 the generally helical direction of the flow of exhaust gases through the muffler, and indicates by the directions of the arrows alternate size gas expansion chambers through which the gases pass.

In operation, the exhaust gases enter the muffler through the flanged opening 13 and are

free to expand to a certain extent in the chamber 22 after which they pass through the openings in the louvers 17 of the first baffle 15 and are directed in a whirling motion by the angles of the walls of the louvers as they enter the first smaller annular expansion chamber 20 enclosed by the wall of the tubular casing 10. Due to continuous pressure on the gases, they enter through the louver openings in the second of the baffles 15 and are started in a helical direction into a larger substantially circular expansion chamber 21 formed by abutting flanges of the second and third baffles 15. This procedure through alternate size and shaped chambers is followed throughout the travel of the gases past the baffles 15 until the gases enter the rear expansion chamber 23 after which they flow through the opening 14 to the atmosphere.

While the bellied walls 16 of the baffles 15 are shown as cone-shaped, it is to be understood that such walls may have their central portions offset by being concavo-convex, conoid-shaped, or any other shape whereby the features above-outlined are attained.

In view of the foregoing description taken in conjunction with the accompanying drawings, it is believed that a clear understanding of the construction, operation, and advantages of the device will be quite apparent to those skilled in this art. A more detailed description is accordingly deemed unnecessary.

It is to be understood, however, that even though there is herein shown and described a preferred embodiment of the invention, various changes may be made without departing from the spirit and full intentment of the invention.

What is claimed is:

1. A muffler comprising a tubular casing having an inlet opening at one end and an outlet opening at the other end; a baffle in said casing adjacent one end thereof and consisting of a circular plate bellied by having the central portion thereof laterally offset toward one end of the tubular casing and having radially extending openings therein that are louvered outwardly from the convex side of said bellied portion in a manner to spirally deflect gases passing through the openings, and a cylindrical flange at the periphery of said circular plate concentric to said tubular casing and extending in a direction opposite to that of said bellied offset portion, said cylindrical flange being in engagement with and secured to the inside of the tubular casing; a plurality of other baffles of identical construction to that of said first-mentioned baffle positioned in said tubular casing between said first-

5 mentioned baffle and the opposite end of the tubular casing with the flanged portions and offset bellied portions alternately reversed relative to one another and to the flanged portion and bellied portion of said first-mentioned baffle thereby arranging the louvered openings of all of said baffles in directions to produce a continuous helical motion to gases passing under pressure through the tubular casing; and means supporting said plurality of baffles in said casing with their flange portions and offset bellied portions in abutting engagement with like portions of adjacent baffles.

2. A muffler comprising a tubular casing having an inlet opening at one end and an outlet opening at the other end; a baffle in said casing adjacent one end thereof and consisting of a circular plate bellied by having the central portion thereof laterally offset toward an end of the tubular casing and having radially extending openings therein that are louvered for spirally deflecting gases passing through the openings, and a cylindrical flange at the periphery of said circular plate concentric to said tubular casing and extending in a direction opposite to that of said bellied offset portion, said cylindrical flange being in engagement with the inside of the tubular casing and secured to said casing; a plurality of other baffles constructed in a like manner to that of said first-mentioned baffle and packed in said tubular casing against said first-mentioned baffle with their flanged portions and offset bellied portions alternately reversed relative to one another and to the flanged portion and offset bellied portion of said first-mentioned baffle, said flanged portions and offset bellied portions being in abutting engagement with like portions of adjacent baffles; and means securing the flange of the baffle of said plurality of baffles that is furthest remote from said first-mentioned baffle to the tubular casing and thereby support all baffles of said plurality of baffles relative to one another and to said first-mentioned baffle.

WILLIAM KELLER.
